CLAIM

The ornamental design for a floatable lounge chair or similar article, as shown.

DESCRIPTION

FIG. 1 is a right side elevational view of a floatable lounge chair or similar article showing my design, the left side being a mirror image thereof;

FIG. 2 is a front elevational view;

FIG. 3 is a rear elevational view;

FIG. 4 is a top plan view;

FIG. 5 is a bottom plan view; and

FIG. 6 is a perspective view thereof.

FIG. 6
